UNITED STATES PATENT OFFICE.

WILLIAM C. BAKER, OF NEW YORK, N. Y., ASSIGNOR TO THE BAKER
HEATER COMPANY, OF SAME PLACE.

CAR-HEATING APPARATUS.

SPECIFICATION forming part of Letters Patent No. 447,100, dated February 24, 1891.

Application filed June 11, 1890. Serial No. 355,033. (No model.)

To all whom it may concern:

Be it known that I, WILLIAM C. BAKER, a citizen of the United States, residing in the city and State of New York, have invented an 5 Improvement in Car-Heating Apparatus, of which the following is a specification.

In heaters for railway-cars, especially dining-room and sleeping cars, the heating-pipes upon one side of the car are often of a different 10 length from the pipes upon the other side of the car and one system of heating-pipes offers more resistance to the circulation of the water than the other. The consequence is that where the two systems are connected as 15 branch pipes to one coiled pipe within the fire-chamber the heating-pipes upon one side of the car are often very much hotter than those upon the other side of the car, and this difficulty arises to an equal extent where there are 20 two heating devices—such as a steam-heater and a fire-heater—acting upon one or more sets or systems of heating-pipes that are united by branches with the circulating-coils.

The object of the present invention is to insure an equal heating action in two systems 25 of radiating-pipes receiving heat from either the fire in the chamber or from steam, and I arrange the connections and the heating-pipes in such a manner as to insure uniformity of 30 circulation and to make use of fire as a source of heat, or steam, or both.

In the drawing I have represented a dia- 35 grammatic view of the circulating systems and a section of the steam-heating device and of the expansion-vessel.

The systems of radiating pipes, coils, or radiators within the car are to be of any desired character, and there are two systems, one of which terminates at the pipes A A' and the 40 other of which terminates at the pipes B B', and there are two coils C and C' in the fire-chamber. These coils are preferably of the same or nearly the same size as the pipes A A' B B', and the general contour of the coils is conical, and I prefer to bend the tubes in 45 forming the coils so that the coil C' will set closely up against the under side of the coil C, in order that the proper space may be left between the respective convolutions for the heat 50 to act equally upon both pipes of the coil with-

out necessarily enlarging the fire-chamber or interfering with the proper combustion of the fuel, and the coil C is connected at its lower end with the pipe A of the system of circulating-pipes A A' and the coil C' is connected 55 at its lower end with the pipe B of the system of heating-pipes B B', and the outer and upper ends of the coils C C' are connected by rising pipes D D' to the water-reservoir or expansion-vessel E, which expansion-vessel is suffi- 60 ciently large to allow for the expansion of the water in the two systems of radiating-pipes, and from this expansion-vessel E the descending circulating-pipe F connects with the pipe B' of one circulating system and the descend- 65 ing pipe F' connects with the pipe A' of the other circulating system.

I prefer to make the expansion-vessel E either in the form of two separate vessels of ordinary size and character, or to divide such 70 expansion-vessel into two parts by a partition G, having a small opening 2 at the bottom below the water-line and a larger opening 3 above the water-line. To this expansion-ves- 75 sel E the ordinary filling-cock H and funnel I are affixed, together with a safety-valve or safety-vent, as at K, which parts may be of any desired character.

It will be understood that there being two 80 circulating systems for the car and in conse- quence of one often having a greater resist- 85 ance than the other, it is preferable to keep the two systems separate throughout, so that the hot water may not follow the route of least resistance, as might be the case if one expan- 90 sion-vessel E only were made use of or in case the partition G were dispensed with, and under all circumstances the fire heat acting upon the coils C C' and heating the water in such coils it becomes lighter, so that the heavier water 95 in the descending columns F F' insures a per- fect, rapid, and nearly uniform circulation through the respective circulating coils or systems of heating-pipes in the car.

The small opening or pipe at 2 between the 95 two expansion-vessels or separate chambers of the expansion-vessel allows for the water- level to be the same in both vessels, and this opening is not sufficiently large to interfere with the action of the separate circulating 100

systems, and the opening at 3 or a pipe between two expansion-vessels will allow hot water or steam to pass from one to the other in case the pressure becomes excessive and the 5 safety-vent K is ruptured, or a safety-valve at this point may be opened by the pressure.

It is advantageous to provide means for 10 heating the water in the separate circulating systems by the action of steam. With this object in view I provide, whenever desired, the coils L L', which are preferably of copper and are introduced above the fire-chamber of the heater as part of the ascending circulating system between the coils in the fire-chamber and the expansion-vessel. These coils are 15 inclosed, preferably, by one chamber or vessel M, to which steam is admitted by a pipe N and cock O, and the water of condensation passes off by the pipe P from the bottom of 20 the vessel M. The steam admitted by the pipe M will usually be supplied from the locomotive by suitable pipes extending along the train of cars.

It will be apparent that where the cars are 25 intended for very cold climates it is often necessary to increase the heating capacity of the apparatus. The present invention allows for so doing without requiring a second fire. By using two expansion-vessels connected together the water can be supplied at one opening, only one safety-vent is needed, and the 30 vessels can be located either together or separate at opposite sides of the smoke-pipe, or wherever most convenient and without changing the general arrangements of the heating 35 apparatus, and ample capacity is provided for

expansion, which is found in practice to be of advantage, especially when the heating capacity is increased.

I claim as my invention—

1. The combination, in a heating apparatus, of two separate systems of pipes or radiators containing circulating water, two separate coils in the fire-chamber, two expansion-vessels connected below the water-line, a supply-cock and safety-vent, and connections between the expansion-vessels and the coils and between the expansion-vessels and the systems of circulating radiator-pipes, substantially as set forth. 40

2. The expansion-vessel for car-heating apparatus having a partition and openings therein above and below the water-line, substantially as specified.

3. The combination, in car-heating apparatus, of two systems of pipes or radiators for circulating water, an expansion-vessel divided into two parts and having connecting openings above and below the water-line, and supply-cock and safety-vent, two coils in one fire-chamber, connections from the expansion-vessel to the upper ends of the coils and to the systems of heating-pipes and connections from the other ends of the systems of heating-pipes to the lower ends of the coils in the fire-chamber, substantially as set forth. 55 60 65

Signed by me this 9th day of June, 1890.

W. C. BAKER.
